BY James N. Ramsey

ATTORNEY.

UNITED STATES PATENT OFFICE

GEORGE ASHTON, OF CINCINNATI, OHIO, ASSIGNOR TO THE CENTRAL FROG & SWITCH COMPANY, OF CINCINNATI, OHIO, A CORPORATION OF OHIO

TRACK BRACE

Application filed April 9, 1929. Serial No. 353,774.

This invention relates to an improvement in rail or track braces, and more particularly to track braces which are adjustable for rails of different sizes.

The primary object of this invention is to provide an adjustable track brace of extremely rigid construction which can be easily and quickly applied to the rails, or removed therefrom, and which has means for preventing the turning of the tie-rod within the rail clips, whereby the necessity of holding said tie rod is eliminated when installing my improved track brace.

Another object of my invention is to provide a track brace having holding means whereby the tie rod is prevented from turning within the rail clips, said holding means being accomplished in a simple, efficient and economical manner.

My invention consists in providing a flattened surface on the threaded ends of the usual tie rod adapted to engage a coacting flattened surface within the rail clips, and in the construction, combination, location and arrangement of parts, as hereinfully set forth and claimed.

In the drawings:

Fig. 1 is a side elevation of the improved brace shown applied to a track, the rails of which appear in vertical section;

Fig. 2 is a plan view thereof;

Fig. 3 is an inside elevation of one of the rail clips;

Fig. 4 is a vertical section on the line 4—4 of Fig. 3;

Fig. 5 is a cross section of the tie-rod on the line 5—5 of Fig. 1; and

Fig. 6 is a perspective view of one of the rail clips and a threaded portion of the tie rod received thereby.

In the embodiment of my invention as illustrated and which shows a preferred construction I provide a track brace comprising tie rod 7 which extends beneath the rails 8 of the track and which is longer than the

width of said track. The ends of said tie-rod 7 are provided with threads 9. Each of the rail clips 10 is provided with a longitudinal hole 11 (Figs. 3 and 4) to slidably receive the tie-rod 7. For each pair of rail clips 10 I provide a pair of clamping nuts 12 and locking nuts 13, as clearly illustrated in Figs. 1 and 2, respectively. Each of the rail clips 10 is provided with a shelf 14, which shelf engages the flange 15 of rail 8 and an overhanging lip or flange retaining member 16 which engages the outer edge and upper surface of said flange 15, as clearly shown in Fig. 1, said lip being strengthened by means of ribs 17. As clearly shown in Fig. 3, the longitudinal hole 11, through each rail clip 10, is provided with a flattened side 11^a and, as clearly illustrated in Figs. 1, 2, 5 and 6, respectively, the threads 9 of the tie-bar 7 being provided with a flattened portion 7^a.

When installing a track brace made according to my invention it is not necessary to hold the tie-bar 7 when tightening the clamping nuts 12 and locking nuts 13, due to the fact that the flattened portion 7^a of said tie-rod engages the flattened portion 11^a of hole 11 and thereby prevents said rod 7 from being turned within the longitudinal hole 11 within the rail clips 10.

Some of the advantages of this invention are that they hold the track to gage on bad curves and prevent rails from turning over; they also prevent the track from spreading or lifting the spikes and where ties are rotted and will not hold spikes a few of these novel braces will keep the track safe. Said braces can be installed in four minutes and can be used over and over again.

Another advantage of this invention is that the rail clips 10 are very strong and durable and clamp all four sides of the flange or base of the rail and hold it as in a vise when the clamping nuts 12 and locking nuts 13 are screwed home against said clips.

Still another advantage of my invention

is the simple and efficient means for permitting the track rails to be adjusted laterally in either direction independently of each other and at the same time having simple and efficient means for holding the tie rod from turning during these various adjustments.

It will be understood that certain changes and modifications of the invention can be made without departing from the scope or 10 spirit thereof as defined in the claim.

What I claim as new and desire to secure by Letters Patent is:

In combination with a track rail, a pair of rail clips adapted to embrace the rail flanges, 15 respectively, a non-circular hole through each clip and disposed in alinement with each other, a tie rod having a threaded end portion intersected by a non-circular portion, the non-circular portion of said threaded end 20 portion engaging the non-circular portion of said non-circular holes, respectively, a nut on said tie rod on each side of said rail and adapted to be screwed toward or away from its adjacent clip whereby said rail may be 25 adjusted laterally in either direction independently of the other track rail.

GEORGE ASHTON.
